UNITED STATES PATENT OFFICE.

EMIL ANDERSON, OF NEW YORK, N. Y., ASSIGNOR TO THE UNIVERSAL TURBINE COMPANY, OF JERSEY CITY, NEW JERSEY, A CORPORATION OF NEW JERSEY.

TURBINE.

1,083,909

Specification of Letters Patent.

Patented Jan. 13, 1914.

Application filed May 21, 1912. Serial No. 698,679.

To all whom it may concern:

Be it known that I, EMIL ANDERSON, a citizen of the United States, and a resident of the city, county, and State of New York, have invented certain new and useful Improvements in Turbine-Engines, of which the following is a specification, reference being had to the accompanying drawings, forming a part thereof.

10 My invention relates to turbine or rotary impact engines and its object is to provide an apparatus of simple construction by which the power in an elastic fluid may be developed efficiently.

15 I will describe my invention in the following specification and will point out the novel features thereof in appended claims.

Referring to the drawings which illustrate an embodiment of my invention, Figure 1 is a sectional side elevation of an engine of a preferred construction. The same apparatus is shown in sectional end elevation in Fig. 2. The other figures, drawn on a larger scale, illustrate certain details of construction. Of these Fig. 3 is a sectional end view of adjacent portions of the stationary element and its coöperating rotor. Fig. 4 is a developed plan view of that part of the rotor which is shown in Fig. 3. A still 30 smaller part of the rotor is shown in side elevation on a further enlarged scale in Fig. 5 with a part broken away to illustrate the construction of the rotor buckets. Fig. 6 is a sectional side elevation and Fig. 7 a plan 35 view of a bucket dividing member which forms a part of the rotor structure. One of the groups of the fluid passages in the stator is illustrated in end elevation in Fig. 8 and the construction of this part of the apparatus is shown more in detail in Figs. 9 and 40 10 which are sectional side elevations taken respectively on the lines 9—9 and 10—10 of Fig. 8. Fig. 11 is a plan view of a part of the rotor developed with the adjacent parts 45 of the stator shown in a section taken on the irregular line 11—11 of Fig. 8. Certain of the parts which are shown in Fig. 1 are drawn on a larger scale in Fig. 12. This figure is added to more clearly show the construction and arrangement of these parts. 50 Fig. 13 is a fragmentary plan view of one of the nozzle-plates and the adjacent portion of the part which holds them.

Like characters of reference designate corresponding parts in all of the figures.

The engine is supported upon a hollow foundation 10 to which is bolted the base 11 of an annular member 12 to which is connected the pipe 13 from some suitable source of fluid pressure supply. The annular member 12 is hollow and forms a supply chamber 14 which encircles the engine. The inside of member 12 forms a cylindrical surface in close proximity with the outer periphery of the rotor. At intervals, preferably spaced 60 equidistantly in this part of the annular member are inserted nozzle-plates 15 through which are cut the inlet nozzles 16 which are connected with the chamber 14 by passages 17. The ends of these plates are 65 provided with beveled edges as shown in Fig. 2, which fit into grooves in member 12 which grooves have undercut edges to fit them. The nozzle-plates are also tapered lengthwise and their receiving grooves are 70 also tapered as shown in Fig. 13. This construction makes it possible to hold the nozzle-plates in place and to remove them or to replace them at will with others having like nozzles or nozzles of different size or shape. 75

The main frame of the engine comprises two side members 20 which are secured to the central annular member 12. These form outlet chambers 21 at either side of the stator, which communicate with the hollow 80 foundation 10 through exhaust connections 22. In their central portions the side members are each constructed to form portions of the stuffing boxes 23 for the shaft 24 and to support bearing brackets 25 for this shaft. 85

The shaft is supported by ball-bearings 26 in these brackets. On one end of it, a ball thrust-bearing 27 abuts on one side against a shoulder formed on the shaft itself and on the other side against an adjusting collar 28. A similar thrust bearing 29 abuts against the other side of this collar and is held against it by nuts 30 threaded onto a reduced end of the shaft. The collar 28 is threaded into the bracket 25 on this end of the engine and may be moved in or out by being turned in one direction or the other. In this way the longitudinal position of the shaft may be adjusted. When it has been set in the desired position it is held 95 there by a set-screw 31 which passes through the bracket onto the collar 28. The ends of both bearing brackets are closed by threaded end plates 32. 33 is a coupling member on one end of the shaft. 100

105

110

40 designates the side plates of the stator. These are clamped between the side members 20 and an annular web 18 projecting inwardly from the member 12.

5 41 is packing and 42 metallic packing rings inserted between grooves around the inner surface of the side plates 40 and the adjacent sides of the annular web 18. These form fluid-tight joints and serve to hold the 10 nozzle-plates 15 in place. At intervals about the inner faces of the side plates they are cut out as at 43 to form fluid passages. Near the outer edges of these passages are placed deflecting vanes 44. In order to facilitate 15 manufacture and to make a practicable structure in which the passages may be made of desired form, the side plates 40 are faced with thinner supplemental plates 45.

The preferred shape of one of the 20 passages 43 is illustrated in Figs. 8 and 9 from which it may be seen that its ends are cut through the supplemental plate, the outer end at 46 and the inner end at 47 and that both of these openings are in a plane transverse to the axis of the shaft 24. In circumferential alinement with opening 47 are two other openings 48 and 49 through supplemental plate 45 which lead into another fluid 25 passage 50. 51 is another outlet opening 30 from this passage through plate 45 inside of the opening 49 but preferably tilted slightly out of radial alinement therewith. 52 is another opening through the supplemental plate 45 which registers with an exhaust 35 passage 53 through side plate 40. These exhaust passages have their sides in substantially radial lines and are of such a length that the outer and inner ends thereof are in circumferential alinement with similar 40 ends of openings 49 and 51 respectively. It is to be noted that all of the aforesaid openings are in a single plane and it is to be understood that not only are these sets of 45 passages and openings duplicated at intervals about the circumference of the side plates but that opposite each set in one of the side plates a similar set faces it in the other side plate.

The essential parts of the stator and other 50 stationary parts of the engine have now been described and I will now describe the construction and arrangement of the rotor. This is built up upon a wheel, the hub of which designated by 60 is affixed to the shaft 55 24. The rim 61 of this wheel is connected by spokes 62 with the hub. Its outer periphery is faced cylindrically to receive a tire-like ring 63 in which are cut alternately directed intake ducts 64, 65. The outside 60 of this ring is finished to fit somewhat closely the inner surface of the annular member 12 and its edges as well as the sides of the part 61 of the wheel are turned to fit between the side plates 40, 45. In the opposite sides of the wheel-rim 63 two annular

grooves 66, 67 are cut preferably of rectangular cross-section. These are of equal depth but the outer grooves 66 are considerably narrower than the inner grooves 67. The buckets fit into these grooves and become parts of the rotor. I have invented a novel construction for this part of the apparatus which I will proceed to describe. A ring 70 having a rectangular cross section is made with a transverse thickness equal to 70 the depth of one of the grooves 66 but of less radial thickness than the width of the groove. Into one side of this ring the buckets 71 are cut extending all the way across the face of the ring. Referring particularly to Figs. 4-7, the form and construction of these buckets may be easily seen. Each bucket is cut into the ring at an angle to the face of the ring so that its outer opening is between the parallel lines 75 72-73 and its inner surface is on a curve 74 under the face of the ring. This is shown in plan view in dotted lines in Figs. 7 and 11. They are then open at top and bottom. 75 is a bucket wall for dividing each bucket 80 into two communicating chambers. These are conveniently made separately and riveted to top and bottom flanges 76, 77 which fit over the outside and inside of bucket ring 70 respectively and are riveted thereto as 85 shown in Fig. 6, thereby serving to hold the walls in position and forming the outer and inner peripheries of ring 70. The whole ring when thus made with the desired number of buckets therein is slipped into groove 90 100 66 and secured to the rotor rim 61. The two outer bucket rings are substantially alike with all of the buckets inclined in the direction of rotation and the two inner bucket rings are also similarly made and fitted into 105 the rotor grooves 67. The inner rings are however so secured to the rotor rim 61 that their circumferential position thereon is adjustable; that is they may be rotated slightly in relation to the outer rotor rings and then 110 rigidly secured to the rotor. I will now describe the operation of this engine. Motive fluid such as steam is admitted to the annular chamber 14 from which it has access through the passages 17 and nozzles 16 to 115 the intake ducts 64, 65 on the rotor. The nozzles flare inwardly to provide for the expansion of the motive fluid so that its pressure is reduced to practically condenser pressure and its potential energy changed to 120 kinetic energy in the form of the velocity of its mass.

From Fig. 11 it may be seen that the ducts 64, 65 are of substantially the same width as the longitudinal length of the nozzle orifice 125 16. The motive fluid will pass through one of these ducts to one side being deflected somewhat to the rear on account of the shape of the duct and will pass from it through the opening 44, which is in circumferential 130

alinement with it, into the passage 43. The impact of the fluid upon the forward face of the duct 64 will have a tendency to drive the rotor forward. As the fluid passes into 5 passage 43 it will be deflected downward by the plates 44, and as the fluid emerges from passage 47 it passes into one of the rotor buckets 71 on the outer bucket ring. The parts are so spaced that when the nozzle 10 outlet is in alinement with one of the ducts 64 the fluid will pass into the large bucket opening at the rear of the division wall therein and pass to the inner curved end of the bucket around the wall 75 and out at the 15 bucket opening in advance of the division wall. In doing this not only is its direction of flow reversed but the bucket is so formed that it provides a path progressively reduced in area so that while the engine is running 20 the velocity of the fluid is decreased and a part of its kinetic energy is transformed into pressure which acts against the pocket part of the bucket adjacent its curved wall 74, thus effectively propelling the rotor. 25 But if the rotor does not rotate, further movement of the motive fluid is arrested by the supplemental plate 45 so that all of the energy of the motive fluid is present as useful pressure. Thus the full force of the 30 fluid is available for starting. It is to be noted that while one of the ducts 64 is in register with one of the nozzles 16, no motive fluid can enter the other side of the rotor through one of the ducts 65. As soon 35 as the rotor has advanced slightly the fluid can escape from the smaller end of the rotor bucket in which it has been thus entrapped through the opening 48 into passage 50 and out through opening 49 into another of the 40 outer series of rotor buckets. Here again the fluid enters the larger end of this bucket and its direction of flow reversed and its velocity reduced therein if the rotor is revolving, or is entrapped in this bucket if the 45 rotor moves slowly until the forward side of this next bucket has moved up to the exhaust port 52, 53 through which it escapes into the chambers 22 out of which it is led through exhaust connections 22 in the hollow 50 foundation base 10 which is open to the atmosphere or which may be connected with condensers if preferred. At the time the fluid emerges from one of the rotor buckets 71 through opening 48 it strikes deflectors 55 54 which turn some of it downward so that it will pass through passage 50 and opening 51 into one of the rotor buckets of the inner buckets from which it can pass into the exhaust passages only after the rotor has advanced slightly. Here it also performs useful work in driving the rotor. The areas of the ports and buckets are so proportioned 60 and designed as to allow for the expansion of the motive fluid so that it emerges through 65 the exhaust ports under no pressure. In

other words, although its velocity is checked at different points along its path of travel, this path as a whole is of increasing capacity in order to provide a free path for the expanding fluid. A slight advance of the 70 rotor brings the nozzle 16 out of register with the duct 64 thereby cutting off its flow through the channels which have been pointed out, and into register with one of the oppositely directed ducts 65 and the 75 operation above described will then take place on the opposite side of the rotor. Of course similar operations are also performed at each nozzle and at each of the opposite sets of stator ports and passages. The various 80 passages from the nozzles to the outlet ports on both sides of the rotor are constructed of serially increasing areas with the exception of the restrictions in the rotor buckets so that when the engine is running 85 at normal speed, the paths for the fluid increase in area in proportion to the expansion of the fluid. Consequently the kinetic energy of the fluid is changed from pressure into velocity and is not utilized as pressure except in starting the engine and to a certain extent in the buckets. It is to be noted that in addition to the impact impulses delivered to the rotor, it receives other reaction impulses when the motive fluid escapes 90 from the ducts 64, 65 against deflecting vanes 44, and from the buckets against deflecting vanes 54. 95

By this novel construction a high starting torque is obtained without waste of motive fluid, as the latter cannot be blown through the apparatus when it is at rest. It cannot pass from the intake to the exhaust without moving the rotor. Not only is a high starting torque obtained, but the engine runs efficiently at intermediate speeds and develops its full power at comparatively low speeds. Moreover, the engine is prevented from racing when running idle or under a light load. This is because of the fact that as herein disclosed, the paths for the fluid are so designed that at normal speed they provide paths which enlarge to provide for the expansion of the motive fluid so that it may pass through the engine at full velocity. 100 On account of this fact, if the rotor rotates at a higher rate of speed than that for which the apparatus is designed, these passages will be interrupted and free flow of the fluid checked. 105 110 115

The apparatus which I have shown to illustrate my invention is one having a horizontal shaft. When the shaft is vertical I prefer to provide larger fluid passages on the lower side of the rotor than those above 120 it in order to counteract the weight of the rotor and its connected parts. I have constructed other embodiments of my invention as it is capable of wide modification, but have selected the particular form herein 125 130

shown and described as suitable for the purpose of disclosing and illustrating my invention.

What I claim is:

- 5 1. A turbine comprising a rotor having buckets on the lateral sides thereof, means for introducing motive fluid into the rotor at its periphery, and a plurality of ducts for alternately directing said fluid to the buckets on opposite sides of the rotor.
- 10 2. A turbine comprising a rotor having a plurality of buckets on the lateral sides thereof, a nozzle directed toward the periphery of the rotor, a plurality of directing ducts on the periphery of the rotor alternately leading to opposite sides of the rotor, and a stator, having intermediate passages between said ducts and the rotor buckets.
- 15 3. A turbine comprising a rotor having a plurality of buckets on the lateral sides thereof, the buckets on each side being in circumferential alinement with each other, an expansion nozzle directed obliquely toward the periphery of the rotor, a plurality of curved directing ducts cut obliquely through the periphery of the rotor alternately leading to opposite sides of the rotor, and a stator having intermediate expansion passages between said ducts and the rotor buckets.
- 20 4. A turbine comprising a rotor having a plurality of buckets on the lateral sides thereof, the buckets on each side being in circumferential alinement with each other, an expansion nozzle directed obliquely toward the periphery of the rotor, a plurality of curved directing ducts cut obliquely through the periphery of the rotor alternately leading to opposite sides of the rotor, and a stator comprising side plates adjacent the lateral sides of the rotor, said plates being provided with intermediate expansion passages between said ducts and the rotor buckets, and exhaust ports through both of said side plates in advance of the nozzle and said stator passages.
- 25 5. A turbine comprising a rotor having a plurality of buckets on the lateral sides thereof, a plurality of nozzles disposed about the periphery of the rotor directed obliquely toward the periphery of the rotor, a plurality of directing ducts on the periphery of the rotor alternately leading to opposite sides of the rotor, a stator having intermediate passages between said ducts and the rotor buckets, and exhaust ports through opposite sides of the stator in advance of each nozzle and its coöperating stator passages.
- 30 6. A turbine comprising a rotor having buckets on the lateral sides thereof and directing ducts on its periphery, a stator surrounding the sides and periphery of the rotor, a nozzle arranged to direct an expansive motive fluid into said ducts, side passages in the stator for leading said fluid from the

ducts into the buckets, and outlet ports through the stator in advance of the nozzle, said nozzle and ducts and passages being of progressively enlarging cross-sectional areas, the buckets being constructed to form a path of progressively decreasing cross-sectional areas from said stator passages to the exhaust ports. 70

7. A turbine comprising a rotor having buckets on the lateral sides thereof and directing ducts on its periphery, a stator surrounding the sides and periphery of the rotor, a nozzle arranged to direct an expansive motive fluid into said ducts, said stator being constructed with side passages for leading said fluid from the ducts into the buckets, and with outlet ports in advance of the nozzle, said nozzle and ducts and passages being of progressively enlarging cross-sectional areas, the buckets being constructed to form a path for the motive fluid of progressively decreasing cross-sectional areas from said stator passages to the exhaust ports and to change the direction of flow thereof. 75

8. A turbine comprising a rotor having a set of buckets on the side thereof and a plurality of directing ducts on its periphery, a stator having portions adjacent the side and periphery of the rotor, a nozzle through the portion of the stator adjacent the rotor periphery, said stator being constructed to form a passage through the portion thereof adjacent the side of the rotor, and an eduction port, said ports being so disposed as to open a passage from the nozzle into the buckets at one position of the rotor, and to open a passage from the buckets to the eduction port at another position of the rotor. 90

9. A turbine comprising a rotor having buckets on the side thereof and a plurality of directing ducts on its periphery, a stator having portions adjacent the side of the rotor and its periphery, a nozzle through the portion of the stator adjacent the rotor periphery, the directing ducts being successively in register with the nozzle during the rotation of the rotor, said stator being constructed to form a passage arranged to lead the motive fluid from one of the ducts when the latter is in register with the nozzle to the rear end of one of the buckets, and with a wall to close the forward end of the bucket, and with an eduction passage in advance of said wall. 100

10. A turbine comprising a rotor having buckets on the lateral sides thereof and a plurality of directing ducts on its periphery alternately leading to opposite sides of the rotor, a stator having portions adjacent the sides and periphery of the rotor, a nozzle through the portion of the stator adjacent the rotor periphery, the directing ducts being successively in register with the nozzle 110

115

120

125

130

14. A turbine comprising a rotor having a plurality of directing ducts on its periphery alternately leading to opposite sides of the rotor, and a stator constructed to form an annular chamber surrounding the rotor and with nozzle passages leading at intervals to said directing ducts. 70
15. A turbine comprising a rotor having buckets on the sides thereof and a plurality of directing ducts on its periphery alternately leading to opposite sides of the rotor, and a stator constructed with nozzle passages leading to said directing ducts and with passages leading from said ducts to the rotor buckets. 75
16. A turbine comprising a rotor having buckets on the sides thereof and a plurality of directing ducts on its periphery alternately leading to opposite sides of the rotor, and a stator constructed to form an annular chamber surrounding the rotor, and nozzle passages leading at intervals to said directing ducts and with other passages at the sides of the rotor leading from said ducts to the rotor buckets. 80
17. A turbine comprising a rotor having buckets on the sides thereof and a plurality of directing ducts on its periphery alternately leading to opposite sides of the rotor, and a stator having a cylindrical portion surrounding the periphery of the rotor, and a removable tapered nozzle block having undercut edges, set into the cylindrical portion of the stator and having its inner surface in alinement with the surface of said cylindrical portion of the stator said stator being constructed with passages at the sides of the rotor leading from said ducts to the rotor buckets. 90
18. A turbine comprising a rotor having buckets on the sides thereof and a plurality of directing ducts on its periphery alternately leading to opposite sides of the rotor, and a stator comprising plates adjacent the sides of the rotor and having a cylindrical portion surrounding the periphery of the rotor; and a plurality of removable nozzle blocks having undercut edges, set into the cylindrical portion of the stator at equally spaced positions, with the inner surfaces of said blocks in alinement with the surface of said cylindrical portion of the stator, said nozzle blocks being held against transverse movement by said plates said stator being constructed with passages at the sides of the rotor leading from said ducts to the rotor buckets. 105
19. A turbine comprising a rotor having buckets on the sides thereof and a plurality of directing ducts on its periphery alternately leading to opposite sides of the rotor, and a stator having a cylindrical portion surrounding the rotor, and plates at the sides of the rotor: said stator plates being constructed to form passages intermediate 110

said ducts and the rotor buckets, and having supplemental plates adjacent the sides of the rotor, said supplemental plates being constructed to form ports at the ends of said passages.

- 5 20. In a turbine, a rotor having an annular groove in the side thereof, a bucket-ring constructed with buckets cut transversely therethrough, and with a blade partly dividing each bucket, affixed to flanges arranged to close the ends of said buckets and to form the inner and outer part of the bucket-ring, said bucket ring being arranged to fit into the groove in the rotor.
- 10 21. In a turbine, a rotor having a plurality of annular grooves in the side thereof, and a bucket-ring for each groove, said bucket-rings being relatively adjustable circumferentially.
- 15 22. In a turbine, a rotor having a plurality of annular grooves in the side thereof, a plurality of bucket-rings constructed with buckets cut transversely therethrough, and

with a blade partly dividing each bucket, affixed to flanges arranged to close the ends 25 of said buckets and to form the inner and outer part of the bucket-rings, said bucket-rings being arranged to fit into the grooves in the rotor, and arranged to be relatively adjustable circumferentially.

30 23. In a turbine, a rotor having a plurality of buckets in the side thereof, each having a curved wall adapted to reverse the direction of flow of motive fluid passing therethrough, and a wall extending from the 35 side of the rotor into the bucket toward said curved wall dividing the bucket into two communicating compartments of progressively decreasing cross-sectional area.

In witness whereof, I have hereunto set 40 my hand this 20th day of May 1912.

EMIL ANDERSON.

Witnesses:

F. B. GRAVES,
G. R. QUIMBY.
